UNITED STATES PATENT OFFICE

2,141,777

RACING GAME

John Watling, Chicago, Ill., assignor to Watling Scale Company, Chicago, Ill., a corporation of Illinois

Application March 20, 1937, Serial No. 132,142

36 Claims. (Cl. 273—86)

This invention relates to the general art of amusement devices, and has reference more particularly to a simulated racing game of that type wherein a race course of fixed length is provided over which a plurality of dummies, such as horses or dogs, move under mechanically applied power, and wherein a freely movable chance or permutation element is introduced that determines which of the dummies will win a given race; the operation of the chance element being such that the owner or operator of the device cannot "fix" it to cause any particular dummy to win, and the likelihood that the same dummy will win two or more successive races is virtually eliminated, thus providing in the operation of the apparatus practically the same uncertainty as to the outcome of the contest as exists in any fairly conducted animal race contest.

The main objects of the invention, partly indicated in the foregoing statement, are: to provide a mechanical racing game of the character indicated that can be manually operated, and by its close simulation of what occurs in a natural animal race, will afford zest and thrill to the player and onlookers; to provide a mechanical racing game apparatus that cannot be "fixed" in advance to determine the winner; to provide a game apparatus wherein the outcome will depend on the position in which a freely movable chance or permutation element comes to rest, to provide a game apparatus wherein, as soon as the winning dummy has reached the goal, the operation of the apparatus will be intermittent and the remaining dummies will stop, to provide a game apparatus wherein, when it is started in operation, the dummies will first be retracted from the goal end of the course to the starting end and lined up at the latter, and will then start down the course and during the racing period the dummies will successively be given accelerated speed; to provide automatic means for varying the duration periods of such accelerated speed movements so that one dummy may receive a short acceleration of its speed, another a longer acceleration, a third a still longer acceleration, etc.; and to provide a mechanical racing game apparatus of the general character above indicated which may be started in operation by a swinging movement in one direction of a single handle lever and in which all the synchronized movements of the parts of the apparatus are entirely automatic to the conclusion of the race.

Numerous other objects and advantages of the invention as an amusement device of the me-

chanical racing type will become apparent to persons familiar with such devices from the following detailed description of an approved embodiment of the invention illustrated in the accompanying drawings, in which—

Fig. 1 is a front side elevation of the machine, partly in vertical section on line 1—1 of Fig. 4, with the parts in the positions they occupy at the termination of the race.

Fig. 2 is a rear side elevation of the same. 10

Fig. 3 is a top plan view of the same, with the racing dummies omitted.

Fig. 4 is a front end elevation of the same, with parts broken away.

Fig. 5 is a rear end elevation of the same, with 15 parts broken away.

Fig. 6 is a longitudinal vertical section, taken on line 6—6 of Fig. 3.

Fig. 7 is a longitudinal vertical section, taken on line 1—1 of Fig. 3. 20

Fig. 8 is an enlarged side elevation of parts shown at the left of Fig. 1, showing a changed position of certain operating parts.

Fig. 9 is an enlarged side elevation of parts shown at the right of Fig. 1, showing a changed 25 position of other operating parts.

Fig. 9a is a section on line 9a—9a of Fig. 9.

Fig. 10 is an enlarged side elevation of parts shown at the left of Fig. 2, showing a changed 30 position of certain parts.

Fig. 11 is a plan section taken on the line 11—11 of Fig. 10.

Fig. 12 is a plan section taken on the line 12—12 of Fig. 8.

Fig. 13 is a plan section taken on the line 35 13—13 of Fig. 9.

Fig. 14 is an enlarged side elevation of parts shown at the left of Fig. 1, showing coin controlled mechanism for releasing a lock and rendering the machine operative on deposit of a 40 coin.

Fig. 15 is a fragmentary front view of the upper portion of Fig. 14.

Fig. 16 is a diagram of the drive mechanism which is actuated manually in one direction to 45 return the racing dummies from the goal end to the starting end of the race course, and by a tensioned power spring in the reverse direction to move the dummies from the starting end to the goal end of the course.

Fig. 17 is a diagram of a cam that controls the 50 accelerating in and out of the devices that effect accelerated speed movements of the dummies and the duration periods of said movements.

For convenience of description the side of the 55

machine shown in Fig. 1 will be termed the front side, that shown in Fig. 2 the rear side, the end shown in Fig. 4 will be termed the front end, and that shown in Fig. 5 the rear end. Also since the dummies are shown as horses, they will hereinafter be identified by that name.

To render the description as clear and orderly as possible, it will be presented under certain functional captions; it being premised that to a considerable extent the mechanisms described under the several captions overlap and interplay with each other.

Frame structure, track rails, and horses

15 The frame structure comprises front and rear uprights 21 and 22 on the front side (Fig. 1) and generally similar front and rear uprights 23 and 24 on the rear side (Fig. 2), top and bottom cross bars 25 and 26 connecting and spacing the uprights 21 and 23 and top and bottom cross bars 27 and 28 connecting and spacing the uprights 22 and 24. The lower portions of the front side uprights 21 and 22 are connected by a tie rod 29 and the lower portions of the uprights 23 and 24 are connected by a similar tie rod 31.

30 Rigidly secured in and supported at their ends by the frame cross bars 25 and 27 (Fig. 3) is a group of parallel equally spaced track rails 32, seven being herein shown, although a greater or less number may be employed. Slidable on the rails 32 are collars 33, on which the horse dummies H are mounted, as shown in Fig. 1.

Horse actuating mechanism return movement

35 Referring to Fig. 4, journaled in and between the upper portions of the front uprights 21 and 23 is a shaft 34, keyed on which is a sprocket wheel 35 through which the shaft 34 is driven in both directions. Also loose on the shaft 34 are sprocket wheels 36, each of which is aligned with one of the track rails 32, as shown in Fig. 3. Keyed on shaft 34 laterally adjacent to the sprocket wheels 36 are discs 37 each carrying on its face pawls 38 cooperating with a ratchet 39 (Fig. 6) fast on the adjacent sprocket 36 to drive the latter counter-clockwise as viewed in Fig. 6, but permitting relative slip of the sprocket on the shaft during the lining up of the horses at the starting post when shaft 34 is rotating in the reverse direction, as hereinafter described.

50 Encircling the shaft 34 between the hub of each disc 37 and the adjacent sprocket is a coil thrust spring 41 that normally creates sufficient friction between each sprocket and its associated driving disc 37 to effect rotation of the sprocket under a rotation of the shaft 34 in said reverse direction.

55 Referring to Fig. 5, journaled in and between the frame uprights 22 and 24 at the rear end of the machine is a shaft 42 parallel with the shaft 34, keyed on which is a sprocket wheel 43 of the same diameter as, and in alignment with, the sprocket wheel 35 and operatively connected with the latter by a sprocket chain 44. Also loosely mounted on shaft 42 is a group of sprocket wheels 45 of larger diameter than, and in alignment with, the sprocket wheels 36 on shaft 34 and operatively connected with the sprocket wheels 36 by chains 46. The collars 33 on the track rails 32 are coupled to the top limbs of the chains 46.

70 The horses are caused to travel back from the goal to the starting point of the course by friction drive of the smaller sprockets 36, and are lined up in a row against the cross bar 25, the sprocket wheels slipping on the shaft as the

several collars 33 strike the bar 25 to such an extent as may be necessary to bring all of the horses in line. This return travel of the horses is effected by manually operated means, next to be described, which also stores energy to propel the horses on the forward or racing movement.

75 Journalized in a vertical wall W (Figs. 3 and 4), which may be a side wall of a cabinet enclosing the machine and having a glass cover, is a stub shaft 47 (Fig. 1), fast on the outer end of which is the operating handle lever 48 of the machine that stands vertical when the machine is idle. Fast on the inner end of the shaft 47 is an arm 49 equipped on its free end with a contact hand 51 (Fig. 4). The handle lever 48 is normally urged to vertical position by a pull spring 52 (Fig. 3) connecting the arm 49 with an anchor pin 53 mounted in the frame member 21. Journalized in and between the uprights 21 and 23 (Fig. 4) is a power shaft 54, loosely mounted on one end of which, just outside the frame member 21, is an oscillatory member, the shaft of which is best shown in Fig. 8, and comprising a hub 55, a sector ratchet 56, and an arm 57, in the free end of which latter is a lateral pin 58 which lies across the path of swing of the hand 51 and is normally in contact with the hand 51 when the machine is idle, as shown in Fig. 1. This oscillatory member is normally urged to the position shown in Fig. 1 by a pull spring 59, and its swing 30 in a clockwise direction, viewing Fig. 1, is limited by a stop pin 61 engaging a shoulder 62 on the sector ratchet 56. Pivoted on a pin 63 on the end of the sector ratchet 56 opposite the shoulder 62 is a trigger member that forms an element of what we term the "kick-off" device, and comprises a nose 64 (Figs. 8 and 14), a rearwardly extending arm 65, and a horn 66 rigid with and disposed cross-wise of the nose 64. On the free end of the arm 65 is a pin 67 extending through an opening in the sector ratchet 56 to which pin is connected one end of a pull spring 68 that is anchored at its other end to a pin 69 on the arm 57 so that the spring 68 normally holds the trigger in the position shown in Fig. 14 wherein the free end of the horn 66 abuts against a removable pivoted coin-controlled stop 71 (later described).

80 Referring to Figs. 4, 8 and 12, keyed on the shaft 54 just inside the frame member 21 is the hub 72 of an arm 73 on which a lateral pin 74 formed with a flat face 75 lies opposite to the end of the nose 64 of the aforesaid trigger when the coin-controlled stop member 71 has been raised from the full line position shown in Fig. 14 to the dotted line position so as to allow the spring 68 to swing the nose 64 up behind the flat face 75 of the pin 74. This pin 74 forms another element of what we term the "kick-off" device.

85 Through these parts when the handle lever 48 is swung downwardly the shaft 54 is turned counter-clockwise viewing Fig. 8 through approximately ninety degrees. Fast on the opposite end portion of the shaft 54, inside the frame member 23 is a quadrant 76 (Figs. 3, 4 and 7), to one end of the periphery of which is attached a sprocket chain 77. This latter, as best shown in Fig. 7, extends over a sprocket wheel 78 fast on a transverse transmission shaft 79 that, as shown in plan view Fig. 3, is journaled in and between the frame members 22 and 24 intermediate the end portions of the frame. Loose on shaft 79 is a large sprocket 81 that is driven in a clockwise direction viewing Fig. 6 by a pawl and ratchet drive 82. As shown in Figs. 1, 2 and 6, the lower

portion of the large sprocket 81 drivingly engages the bottom limb of the sprocket chain 44, thus imparting a drive to the shaft 34 in a direction to move the several chains 46 to which the horses are attached in the proper direction to return the horses from the goal end of the course to the starting end under the friction drive of the sprockets 36 on shaft 34. As best shown in Figs. 1 and 6, the other end of chain 77 is connected to a long spring 83 anchored to one of the forward frame elements, so that, as the horses are drawn back to starting position, the spring 83 is stretched and power is stored therein for moving the horses down the course during the racing period.

The sector ratchet 56 cooperates with a pivoted double nose dog 84 (Figs. 1 and 8) to compel a full down swing of the arm 57 before the latter can return to its starting position under the pull of its return spring 53. The nose of the dog is held engaged with the teeth of the ratchet by a spring 85, and the arm 57 cannot return to its elevated position shown in Fig. 1 until the dog has been backed away from the ratchet, which is done at the end of the racing period by a lateral branch arm 86 integral with the arm 73, the free end of which branch arm strikes a pin 87 (Fig. 12) carried by the dog and extending through an opening 88 in the frame member 21 as the arm 73 reaches the vertical position shown in Fig. 1. The arm 73 swings from the position shown in Fig. 8 to that shown in Fig. 1 during the return rotation of shaft 54 under the pull of the power spring 83 when the horses are racing. Also, to prevent a slamming stroke and compel an easy down stroke of the handle lever 48 the arm 49 is connected by a link 89 and elbow lever 91 (Figs. 1 and 4) to the plunger rod 92 of an ordinary pneumatic dash pot 93 of the door check type.

40 Horse advancing mechanism

As soon as the last horse has been lined up at the starting bar 25, the operator may release the handle bar 48 which will then return to its vertical position, and thereafter the machine is energized by the stored power in the spring 83. This transfer of motive power from the operator to the spring 83 is effected by the so-called "kick-off", two elements 64 and 74 of which have already been described. The third cooperating element consists of a stationary cam 94 (Figs. 4 and 8) loose on shaft 54 between the inner side of the sector ratchet 56 and the frame member 21 that lies in the path of downward travel of the trigger arm 65. This cam has a downwardly extending tail piece 95 adjustably attached to frame piece 21 by a clamp screw 96 passed through an arcuate slot 97 in the tail piece, and adjustment is effected by a screw 98 (Fig. 8). By this means the angular set of the cam 94 on the shaft 54 may be slightly varied to cause the nose 64 of the trigger to slide off the flat face 75 of pin 74 at just the right instant to start the racing operation. This sliding off movement is, of course, effected by contact of the downwardly moving trigger arm 65 with the top side of the cam 94.

The instant this kick-off movement occurs, the stretching of the power spring 83 ceases, and said spring starts its contracting movement, during which movement it rotates the shafts 79 and 54 in the reverse direction to that in which they were previously rotated when returning the horses to starting position and storing power in the spring 83. This reversed rotation of shaft 79 is

transmitted to large sprocket 81 through a clutch mechanism on the opposite side of said sprocket from the ratchet drive 82. This clutch mechanism, as best shown in Fig. 3, comprises a fixed toothed clutch member 99 fast on the sprocket 81, and a cooperating sliding toothed clutch member 101 splined on the shaft 79 and actuated by a pivoted clutch-shifting lever 102. A spring 103 holds the clutch closed during the entire operating period of the machine, the clutch being opened only when the winning horse reaches the goal to stop the machine and leave the remaining horses standing in the respective positions on the race course which they occupy when the winning horse reaches the goal, as shown for example in Fig. 3. The fact that the clutch 99, 101, is closed during the period when the horses are being returned to starting position, and the sprocket 81 is being driven by the ratchet drive 82 makes no trouble, because at that time both members 99 and 101 of the clutch are turning in the same direction at the same speed and there is no relative rotary movement between them. As above stated, the clutch is opened as the winning horse reaches the goal, and this is done by a suitably timed cam hereinafter described. The drive of the shaft 79 counter-clockwise, viewing Fig. 6, through the sprocket 81 and chain 44 imparts corresponding counter-clockwise rotation to the shafts 34 and 42, and this rotation of shaft 34, through the pawl and ratchet drives, positively rotates the sprockets 36 in a direction to effect the forward or advance travel of the top limbs of the horse-impelling chains 46, and this at what we term the low speed. During this movement, the larger sprockets 45 loose on shaft 42 function merely as idlers, except as said larger sprockets are, during the racing period, converted into driving sprockets, taking the drive away from the opposed sprockets 36 and propelling the chains 46 at an accelerated speed for varying parts of the racing period due to the larger diameters of the sprockets 45 relatively to the sprockets 36. This conversion of the sprockets 45 from idlers to drive sprockets is effected by clutches individual to each sprocket wheel, and these clutches are thrown in and out by the chance element.

Chance element and high speed sprocket clutches

The chance element and the high speed sprocket clutches and clutch-shifting devices are best shown in the rear end view, Fig. 5, wherein 104 designates what we term a "free spin" shaft journaled in anti-friction bearings 105 in the frame members 22 and 24, beneath and parallel with the shaft 42. Keyed on this shaft 104 are a plurality of hubs 106, and on one end of each hub is a radial arm 107 to which is attached, at an angle to the arm, a flexible strip 108 that functions as a cam; and behind the arm 107 (relatively to direction of rotation of the shaft) is an arm 109 on which is mounted an oppositely inclined rigid cam 111. Splined on the shaft 42 between each sprocket wheel 45 and a fixed collar 112 on the shaft is a sleeve 113 formed with a ratchet clutch face that is shiftable into and out of engagement with a corresponding clutch 114 fast on the side of the sprocket wheel. The slideable clutch member 113 is engaged by a vertical clutch shifter lever 115 that is pivoted at 116 on a transverse frame bar 117 and is normally held disengaged from the clutch member 114 by a pull spring 118.

The free spin shaft 104 is bodily shiftable end-

wise in its bearings, by means later described, to carry the several cam members thereon into and out of positions to actuate the clutch-shifting levers 115, and also to carry a pinion thereon (later described) into mesh with an actuating rack, said cam members being shown in Fig. 5 in their inoperative positions. Under a step-by-step rotation of the shaft 104, each cam 108 thereon is caused to first close a clutch 113, 114, and then, after a certain period of time, the same clutch is opened by its spring 118. The companion cam 111 insures the opening of the clutch if the spring should fail or the clutch stick. As before stated, when any one of the sprocket wheels 45 is thus coupled to the shaft 42, it becomes an agent for driving its chain 46 at an accelerated speed.

Chance element spinning mechanism

Referring to Figs. 1, 9 and 9a, 119 designates a ratchet wheel fast on the end of shaft 104 that overhangs the outer side of frame member 22. Mounted to slide up and down on the outer side of frame member 22 is a relatively wide plate 121 and mounted to slide up and down on the outer side of plate 121 is a relatively narrow plate 122. In frame member 22 are studs 123, 124 and 125. Plate 122 has vertical slots 126 and 127 engaged with studs 124, 125, and plate 121 has a slot 128 engaged with stud 123 and also slots registering with the slots 126, 127 in plate 122 and engaged with studs 124, 125. By the three studs mentioned both plates are confined and guided for vertical movement with capacity of vertical movement relatively to each other.

On the outer face of plate 122 is pivoted at 129 a dog 131, the pointed lower end or nose of which is normally held substantially in a vertical line tangent to the teeth of the ratchet wheel 119 by a pull spring 132 and stop pin 133. In the inner edge of plate 122 is a notch 134 (Fig. 9), that, in the lowermost position of both plates shown in Fig. 1, is engaged by the squared upper end of the upwardly extending arm 135 (Fig. 9a) of an elbow lever that is pivoted at 136 on plate 121. To the other arm 137 of the elbow lever is connected a pull spring 138 that urges the arm 135 into engagement with the notch 134, as shown in Fig. 1, so that when plate 121 is raised, plate 122 will be raised with it until the catch (arm 135) is dislodged from notch 134. This dislodgment is effected at the proper time by a cam 139 mounted on the outer side of catch arm 135 that wipes across the head of stud 125. Fig. 9 shows the parts in the positions where the plate 122 is just about to drop, causing the dog 131 to strike the ratchet 119 and spin the shaft 104. Plate 122 tends to drop by gravity, but to insure its dropping movement against any frictional retardation of its guide studs 124, 125 a light pull spring 141 is preferably employed. The extent of swing of the elbow lever is limited by a pin 142 in arm 135 engaged with a short arcuate slot 143 in plate 121.

Describing next the mechanism for elevating the plate 121, and referring to Figs. 1, 3, 8 and 9, 144 designates as a whole a long link bar that is preferably made in overlapping sections connected by a spring so as to afford an elastic pull and avoid injury to the parts actuated thereby resulting from a jerky or slamming manipulation of the main handle lever 48. 145 designates the forward section of this link bar, and 146 designates the rear section. Where the two sections overlap, one section (for example section

146) has longitudinal slots 147 (Fig. 1) and the other section 145 has headed studs 148 riding in the slots 147. Section 145 carries a pin 149 extending through the foremost slot 147 and section 146 carries a pin 151. The pins 149 and 151 are connected by a pull spring 152.

The rear end of the link bar has a pivotal connection 153 to one arm 154 of a bell crank lever that is pivoted at 155 to the frame member 22, and the other arm 156 carries a pin 157 engaged with a horizontal slot 158 in plate 121.

Secured to the outer side of the frame piece 21 is an angle bracket, the laterally projecting limb 159 of which (Figs. 4 and 8) has a vertical slot 161 through which extends the link bar section 145, the bottom edge of said slot supporting said section in its lowest position. In the lower edge of said section is a notch 162, appearing in dotted lines in Fig. 8 behind a guard strip 163 slidably mounted on studs 164 carried by the section 145. In the lower edge of the guard strip 163 is a notch 165, which is a duplicate of the notch 162 and is movable into and out of register with the latter. When the link bar is in its extreme forward position illustrated in Fig. 8, the notch 162 is covered by the guard strip under the pull of a spring 166; but just before the link bar has been retracted to its rearmost position by the fall of the plate 121 a pin 167 on the guard strip 163 strikes the bracket 159 (Figs. 1 and 14), and the notches 162 and 165 are thus brought into register.

On the free end of the arm 73 is a stud 168 that, in the idle position of the parts, occupies the registering notches 162 and 165, as shown in Figs. 1 and 14. Consequently, when the handle lever 48 is swung down and the shaft 54 rocked counter-clockwise viewing Fig. 14 through the mechanism previously described, the link bar 144 is drawn forwardly until the stud 168 slips out of the notches 162 and 165, and this forward travel of the link bar raises the plate 121 and with the latter the plate 122 until the latter is caused to drop by the action of the cam 139, as above described, thus spinning the shaft 104. The dropping of plate 121 (later in the operation of the machine) of course returns the link bar 144 to its rearmost position, and the guard strip 163 prevents the stud 168 from entering notch 162 until the plate 121 has dropped to its lowest position.

Mechanism for shifting free spin shaft to operative position

Fig. 5 shows the position of the free spin shaft 104 at the time it receives its spinning movement, in which position its cams are out of operative relation to the clutch levers 115. Just after the shaft spinning operation, the shaft 104 is centered by means later described to operatively relate the cams angularly to the clutch levers and is then given an endwise shift to the right, viewing Fig. 5, to bring its cams into positions to operate the levers 115 by a subsequent step-by-step rotary movement, as hereinafter described.

Describing this shaft shifting means, and referring to Figs. 1, 3, 4, 5, 8, and 13, 169 designates as a whole a long push bar that, like the link bar 144, is preferably made in overlapping sections connected by a spring so as to afford a cushioned pushing action. 171 designates the forward section and 172 the rear section, the inner portions of said sections slidably overlapping (Fig. 3), as in the case of the link bar 144, and connected by pins 173 and 174 and a spring 75

175. To the front face of the forward section 171 is attached by screw studs 176 an adjustable slotted stop strip 177 that, through contact with a slotted guide bracket 178 through which the forward section 171 of the push bar extends, limits the forward movement of the push bar, as shown in the plan view Fig. 3.

As shown in Fig. 13, the rear end of the rear section 172 is pivoted at 179 to one arm 181 of a horizontal bell crank lever that is pivoted at 182 on a bracket 183 attached to the inner side of the frame member 22, and the other arm 184 of the bell crank lever has a forked end 185 (Fig. 5) carrying pins 186 engaged with a grooved collar 187 keyed on shaft 104.

As shown in Fig. 8, the forward end of the push bar 169 lies across the path of a pin 188 (see also Fig. 4) on the rear side of the sector ratchet 56, so that slightly before the latter reaches the position shown in Fig. 8 the bar 169 is pushed rearwardly and the free spin shaft 104 is shifted endwise through the mechanism described. The free spin shaft is returned to its initial position, at the conclusion of the racing period by a spring 189 (Figs. 1 and 3) after the dog 84 has been kicked off the ratchet 56 by the arm 86.

Free-spin shaft turning and centering mechanism

On the rear side of the machine is an escapement-controlled rack and pinion mechanism for effecting an intermittent or step-by-step turning of the free spin shaft 104 as the race progresses, and also a device for preliminarily centering the shaft so that its cams will be operatively related angularly to the clutch levers and the pinion thereon will engage with the teeth of the rack as the shaft is shifted endwise to bring its cams into position to act on the clutch levers 115.

Fast on the end of the shaft 104 that overhangs the frame member 24 is a wide pinion 191 (Figs. 2, 5 and 11) that has as many teeth as there are horses on the race course (seven as herein shown). Vertically slideable on guide studs 192 on the outer side of the frame member 24 is a plate 193 having one vertical edge formed as a rack 194 for cooperation with the pinion 191 and the other vertical edge having escapement teeth 195.

Fig. 2 shows the plate 193 in its lowermost position. During the operation period when the horses are being returned to starting position, the plate 193 is elevated by a mechanism very similar to that employed for elevating the plate 191, this consisting of a long link bar 196, preferably made in two sections connected by a spring 197 to effect a cushion movement. The rear end of the link bar 196 is pivoted at 198 to one arm 199 of a bell crank lever that is pivoted at 201 on the frame piece 24. The other arm 202 of the bell crank carries a pin 203 engaged with a horizontal slot 204 in the plate 193. The link bar 196 is normally urged rearwardly in a direction to exert a lowering effect on the plate 193 by a spring 205 (Figs. 3 and 7). The forward portion of the link bar 196 is supported and guided in a slotted bracket 206 (Fig. 2), and in its lower edge is a notch 207 engaged by a pin 208 on the upper end of an arm 209 that is keyed on the shaft 54 just outside the frame piece 23, as shown in Fig. 4.

70 Keyed on the end of shaft 79 overhanging the outer side of the frame piece 24 is a disc cam designated as an entirety by 211. This cam has the double function of actuating an escapement mechanism by which the plate 193 is lowered step-by-step during the racing period of the ma-

chine, and determining the duration of the periods between successive steps, during each of which periods one of the horses is being moved at accelerated speed relatively to all the others. On the outer face of the cam disc 211 is a lateral pin 212, the function of which will be later described. Pivoted at 213 on the frame piece 22 is an escapement lever 214, the pallets 215 of which are adapted to alternately engage the teeth 195 and temporarily support the plate 193 between successive downward movements. An operating arm 216 carries a pin 217 engaged with a slot 218 in the rearwardly extending arm 219 of a lever pivoted at 221 on the frame piece 24. On the other arm 222 of this lever is pivoted at 223 an upstanding arm 224 equipped with a cam follower 225 the shaft of which rides in an arcuate slot 226 in the lever arm 222. A pull spring 227 normally holds the arm 224 vertical with the follower shaft at the right hand end of the slot 226 viewing Fig. 2. This constitutes a one-way cam follower device which permits the cam 211 to rotate in the direction of the dotted arrow (Fig. 17) during the period when the horses are being returned to the starting position and the spring 83 is being tensioned without operating the escapement mechanism, but does operate the escapement mechanism when the cam disc is turning in the direction indicated by the full line arrow, which occurs during the racing period. 30 A pull spring 228 urges the escapement arm 216 downwardly into contact with an adjustable stop 229, and operates the escapement in one direction.

During the winding up operation, when the horses are being returned to the starting position, the cam 211 makes one complete rotation from the position shown in Figs. 2 and 17 in the direction indicated by the dotted arrow, and during this period the spinning of the shaft 104 occurs, and the plate 193 is raised to its highest 40 position. During this period the pinion 191 is out of engagement with the rack 194, as shown in Fig. 5, so that the shaft is free to spin, retarded only by the slight friction of its bearings. The shaft is then shifted endwise, as has been previously described, to carry the pinion 191 into engagement with the rack 194, but before this is done it is necessary to center the pinion 191 so that its teeth will engage with the teeth of the rack, and this is accomplished by a device 50 next to be described.

Pivoted at 231 on the rear lower portion of the frame piece 24 is an upstanding arm 232, on the inner end of which is a single tooth 233 located directly opposite the pinion 191. The upper portion of the arm 232 is confined, with capacity of a limited edgewise swinging movement, by a stud 234 engaged with a slot 235, and pivoted to the upper end of the arm 232 on a pin 236 is a forwardly extending bar 237, the forward portion 60 of which is laterally offset to overlap the front side of the cam 211 in a position to be struck and raised by the pin 212. A spring 238 anchored at one end to the pin 236 and at the other to the upper stud 192, urges the arm 232 to the vertical position shown in Fig. 2, but permits it to be forced rearwardly to the inclined position shown in Fig. 10. On the lower edge of the bar 237 is a catch shoulder 239 which, in the position of the parts shown in Fig. 10, engages with 70 the upper stud 192 to temporarily hold the arm 232 in the inclined position shown in Fig. 10, wherein the centering tooth 233 is clear of the pinion 191. An adjustable stop 241 (Fig. 10) limits the inward swing of the arm 232 under 75

the pull of spring 238 at a time when the pinion 191 is engaged with the rack bar 194 and is disengaged from the centering tooth 233.

When the machine is at rest, the parts are in the positions shown in Fig. 2, the pinion 191 is disengaged from the rack 194, and the centering tooth 233 is engaged with the pinion 191, as shown in Fig. 5. Obviously, before the shaft 104 can be spun, the tooth 233 must be disengaged from the pinion, and this is done during the rising movement of the plate 193 by a cam 242 on the rear edge of said plate, which engages a one-way follower 243 (similar in operation to the follower 225), which shifts the arm 232 to the rearwardly inclined position shown in Fig. 10, and at the same time the bar 237 drops and the catch 239 engages with the stud 192. This is immediately followed by the dropping of the plate 122 on the opposite side of the machine and the free spinning of the shaft 104. When said shaft comes to rest, the pin 212 on the cam 211 strikes and lifts the bar 237 thus disengaging the catch 239, and the spring 238 brings the centering tooth 233 into engagement with the pinion 191, centering the latter, and this is followed by the endwise shifting of the shaft which carries the cams thereon into operative position to actuate the clutch shifting levers 115 as the shaft is subsequently rotated and also moves the pinion into mesh with the rack 194 and out of engagement with the tooth 233. Incidentally, this centering of the pinion places the shaft 104 in a position such that one of the cams 107 carried by the shaft is in a position to strike and actuate one of the clutch-shifting levers 115 as the shaft is shifted endwise, so that as the racing period starts, one of the horses starts under the impulse of its accelerated speed sprocket 45, thus taking a lead at the very start over the rest of the field.

Referring to Fig. 17, which is a schematic view of the high speed control cam 211 from the same side and in the same position as it is shown in Fig. 2, the periphery of the cam disc has three elevations marked A, B and C having arcuate tops or peaks 2, 4 and 6 respectively, of varying lengths and concentric with each other and the axis of the disc, and inclined sides. Between the starting point S and the approach side of elevation A, the descent side of A and the approach side of B, the descent side of B and the approach side of C, and the descent side of C and the point S are four arcuate bottoms marked 1, 3, 5 and 7 respectively, that are also of varying lengths and concentric with each other and the axis of the disc.

Assuming that the disc starts to rotate counterclockwise, as indicated by the solid arrow, with plate 193 in its highest position, as the follower travels over bottom 1 the high speed drive thrown in by the centering and endwise shifting of the shaft 104, as before described, remains in, and one of the horses takes a lead over the rest of the field at the very start. As the follower climbs A the escapement is actuated, the plate 193 drops one tooth, shaft 104 is given one-seventh of a complete rotation, the first high speed drive (1) is thrown out and another is thrown in which lasts only for the short duration represented by the length of top 2. As the follower then drops off A the escapement is again actuated, plate 193 drops another tooth, shaft 104 is given another one-seventh of a complete rotation, the second high speed drive (2) is thrown out and another is thrown in which lasts

for the duration represented by the length of bottom 3. This continues until the cam disc has completed one revolution, plate 193 has dropped step-by-step to its lowest position, and all of the clutch throw-in and throw-out cams on shaft 104 have successively been caused to function, causing each of the seven horses to be given an accelerated speed of greater or less duration. During this revolution of the cam disc 211, the pin 212 kicks off the catch 239 and allows the arm 232 carrying centering tooth 233 to swing back to vertical position (Fig. 2), so that, as the free spin shaft 104 is drawn back to its first position by its returning spring 189 at the conclusion of the race, the pinion 191 is drawn into engagement with the centering tooth 233 and the free spin ratchet 119 is returned to a position to be hit by the dog 131 (Fig. 5) on the next operation of the machine.

Speed retarding device

To insure the operation of the machine during the racing period, a power storage spring 83 of ample capacity is employed, and to somewhat slow down the speed of the entire field of horses during the race, a speed retarder is employed on the rear side of the machine. This device is in the nature of a pneumatic brake, and, as herein shown, consists of a speed-multiplying gear train designated as an entirely by 244 (Fig. 3) mounted in a box 245 (Fig. 2) attached to the outer side of the frame piece 23. The initial gear of the train is fast on a shaft 246, and loose on the shaft 246 is a pinion 247 that is fast with a disc 248, said disc having dogs 249 engaged with a ratchet disc 251 fast on the shaft 246, and driving said ratchet disc only in one direction. Keyed on the shaft 54 is a toothed sector 252 meshing with and driving the pinion 247. During the winding up period, when the horses are being brought back to the starting point, the gear sector 252 idly rotates the disc 248 of the ratchet clutch. Fast with the shaft of the last gear of the speed multiplying train 244 is a spindle 253 on which is mounted a wind vane 254.

When the power spring 83 assumes the load, and the shaft 54 is turned counter-clockwise viewing Fig. 2, the toothed sector 252 slowly descends, driving the gear train through the one-way ratchet clutch, and rotating the vane 254 at a high speed, and the wind resistance on the vane slows down the drive of the parts in an obvious manner.

Machine movement throw-out

As heretofore stated, the machine is so designed as to its mode of operation that, when the winning horse reaches the goal, the drive of all the horses ceases, and the horses are all stopped in their tracks. This is effected by the following described mechanism.

Referring to the two side views Figs. 1 and 2, 255 designates each of twin arms that are pivoted at their lower ends at 256 to the frame members 22 and 24 and extend above the latter. In the top edge of each arm 255 is a notch 257, and in these notches are seated the ends of a transverse goal bar 258 (Fig. 3). The arms 255 are normally urged inwardly by pull springs 259, as partially indicated in Fig. 9, the extent of both forward and rearward swing of the arms being limited by studs 261 passed through arcuate slots 262 in the upper portions of the arms. In the inner edge of the arm 255 on the front side of the machine (Figs. 1 and 9) is a notch 263 that

receives a pin 264 in the top of the plate 121 when the latter is raised to its highest position, the pin 264 riding over the forward edge of the arm until it reaches the notch 263, whereupon the spring 259 causes the notch to engage with the pin and thus support plate 121 in its fully elevated position until the termination of the race. On the rear side of the upper portion of plate 121 is a vertical cam 265, best shown in Fig. 5, that cooperates with a follower 266 on the rear end of the lever 102 (see Fig. 3) which throws out the clutch member 101 that drives the large sprocket 81.

When the collar 33 carrying the leading horse strikes the goal bar 255, it pushes the latter and the arms 255 rearwardly to the position shown in Fig. 1, which disengages the pin 264 from the notch 263 and allows the plate 121 to drop. Near the end of this dropping movement the cam 265 rides over the follower 266, as shown in Fig. 5, and this disengages the clutch member 101 from its cooperating clutch member 99, halts the drive of sprocket 81, and brings the machine to rest. At this point the quadrant 76 fast on shaft 54 (Fig. 7) should reach its lowest position, in contact with an adjustable stop 267; but if, when the clutch 101, 99 is disengaged by the cam 265, the quadrant 76 has not quite reached its lowest position and the arm 73 fast on shaft 54 has not returned into operative engagement with the link bar 144, the spring 83 continues its pull on chain 77 until said parts are fully restored to starting position.

Coin-controlled lock

Amusement machines of this and similar character, are, like the common penny-in-the-slot weighing machines, usually equipped with a lock that is released by a coin-controlled mechanism upon the deposit of a coin, such as a nickel or a dime, representing the charge of the owner or proprietor of the machine for the privilege of operating it; especially when the machine is located in a public place, such, for example, as a hotel lobby or railway station.

I have accordingly equipped the amusement machine of this application with a simple form of coin-controlled lock; the locking element having been previously referred to as the pivoted coin-controlled stop 71 shown in Figs. 1 and 8. In the idle position of the machine this stop 71 blocks the pivoted trigger member on the sector ratchet 56 from swinging to a position in which its nose 64 can operatively engage the flat face 75 of the pin 74 in order to return the horses to starting position and wind up the power spring 83. The stop member 71 must be lifted out of the way to permit the machine to operate, and this is done by the coin-controlled device, which is principally illustrated in Figs. 14 and 15.

Journaled in and between the upper portion of the frame member 21 and an adjacent vertical bracket 268 bolted to the front cross bar 25 is a shaft 269. Fast with the shaft 269 is an upstanding jaw member 271, and also pivoted on the shaft 269 by half bearings 272 and 273 that are united by screws 274 is a forked jaw 275, the twin members of the fork lying on opposite sides of the jaw 271. Keyed on shaft 269 is an arm 276 carrying a crank pin 277 that is connected by a downwardly extending link 278 with the arm 57. Secured to or integral with one of the rear half bearings 273 is a radially extending arm 279, to the free end of which is connected a

link 281, the lower end of which is connected to the pivoted stop 71.

A pull spring 282 connected to a tail piece 283 of the arm 276, and a similar pull spring 284 connected to a tail piece 285 of one of the bearings 272, 273, maintain the two jaws 271 and 275 in vertical position and separated sufficiently to permit a coin to drop into the space between them, as shown in Fig. 15, the coin being dropped through an overlying chute 286. The coin thus locks the two jaws against relative movement, so that the down pull of link 278 rocks arm 279 upwardly and through link 281 raises the stop 71 to the dotted line position shown in Fig. 14. In the preoperating position of the parts there is sufficient clearance between the trigger nose 64 and the face 75 of pin 74 to permit the stop 71 to be raised before the nose 64 reaches the plane of the face 75.

In practice, the coin-controlled starting mechanism is equipped with means for dislodging the coin from the jaws and delivering it to a coin receptacle after each operation of the machine; but since the coin-controlled mechanism for locking the machine against operation does not, per se, form any part of the present invention, such coin delivery mechanism has been omitted.

Operation

The operation of the apparatus has to a considerable extent been described in connection with the descriptions of the several cooperating mechanisms, but a brief description more particularly setting out the timing or sequence of operation of the several mechanisms may assist an understanding of the apparatus as a whole.

An idle position of the apparatus as the parts appear at the conclusion of a race and before the next operation is started is shown in Figs. 1 to 7 inclusive, in which position the tooth 233 is engaged with the pinion 191 on the free-spin shaft as shown in Fig. 2. The handle lever 48 is drawn downwardly by a slow steady movement; and if the apparatus is equipped with the coin-controlled locking mechanism, a coin is first deposited so that the down swing of the lever raises the stop 71 and permits the trigger nose 64 to rise to a position in which it will strike the pin 74 so that a turning movement is imparted to shaft 54. During this turning movement, the centering tooth 233 is thrown out of engagement with the pinion 191, leaving the free-spin shaft free to rotate, the horses are drawn back to starting position, power is stored in the spring 83, the rack plate 193 is raised to its highest position, plates 121 and 122 are raised, the free-spin shaft is whirled and plate 121 is suspended from arm 255, the centering tooth 233 is then let into engagement with the pinion 191 to center the free-spin shaft, the free-spin shaft is then shifted endwise to carry its pinion 191 out of engagement with the centering tooth 233 and into engagement with rack 194 and its cams into operative relation to the clutch shifters 115, and the cam 211 makes an idle complete revolution in the direction indicated by the dotted arrow in Fig. 17. As the handle lever swings down, the shaft-turning mechanism is locked against a partial stroke by the dog 84 engaged with sector ratchet 56. The "kick-off" (sliding of trigger nose 64 off the face 75 of pin 74) occurs when the handle lever has nearly reached the limit of its down swing (see Fig. 3) at a time determined by the set of cam 94, at which time the dummies have all been lined up at the starting bar 25, 75

and thereupon the load is transferred to the power spring 83 and the dummy-driving devices are operated in the reverse direction by spring 83. During the racing period the free-spin shaft 5 is given a step-by-step rotation by rack 194 and pinion 191 to successively throw in the high speed sprockets 45, the descending movement of the rack being controlled by the escapement mechanism (Figs. 2 and 10) and this latter in turn being controlled by the cam 211 to determine the 10 times at which the free-spin shaft is partly rotated and the duration of the driving periods of the high speed sprockets 45. As soon as the "kick-off" has occurred, the handle lever 48 may be released, and it then returns to upright position under the pull of its spring 52. The arm 57 and parts carried thereby cannot, however, return to starting position until dog 84 has been backed off from ratchet 56, which is done by 15 arm 83 (Fig. 6) as arm 73, fast on shaft 54, slowly returns to vertical position during the racing period. As soon as the ratchet 56 is thus freed, said ratchet and its associated arm 57 return to normal starting position shown in 20 Fig. 1 under the pull of spring 59.

When the winning horse strikes the goal bar 258, the plate 121 is released and drops, and the vertical cam 265 on the rear side thereof actuates the clutch lever 102 (Fig. 3) to open the clutch 30 69, 101, and arrest the operation of the machine, leaving the remaining dummies in various trailing positions as illustrated, for example, in Fig. 3. As the arm 57 thus returns to starting position at the conclusion of the racing period, the pin 188 carried thereby moves away from the 35 end of bar 169, so that the spring 189 can then, through said bar and the parts actuated thereby (Fig. 13), return the free-spin shaft to its inoperative position, thereby bringing the pinion 191 again into engagement with the centering tooth 233 and the driving ratchet 119 of the free-spin shaft into position to be hit by the dog 131 on the next descent of plate 122. This completes the cycle of one operation of the apparatus.

The free-spin shaft 104 is the element of the machine that creates the uncertainty and diversity in the outcome of the race. Rarely, if ever, will successive spinning or whirling movements of the shaft come to rest with the cams thereon in the same position, and this consequently will cause different horses to win successive races. And since the shaft is whirled by mechanical means, and not directly by the operator of the machine, there is no chance for the operator to 55 "fix" the result.

This invention may be developed within the scope of the following claims without departing from its essential features, and the specification and drawings are to be regarded as merely illustrative and not in a limiting sense, except as necessitated by the prior art.

I claim:

1. In a racing game apparatus, the combination of a frame, parallel rectilinear track rails mounted on said frame, endless sprocket chains respectively mounted parallel with said track rails, dummies slidably mounted on said rails and attached to said chains, a power spring, manually operable means for actuating said chains in a direction to effect the return movement of the dummies to starting position and for simultaneously tensioning said spring, means motivated by said spring for actuating said chains at a uniform speed in a direction to effect the racing movement of the dummies, and chance

controlled means for effecting successive increases of speed of the respective chains during the racing movement.

2. In a racing game apparatus, the combination of a frame, parallel rectilinear track rails mounted on said frame, endless sprocket chains respectively mounted parallel with said track rails, dummies slidably mounted on said rails and attached to said chains, a power spring, manually operable means for actuating said chains in a direction to effect the return movement of the dummies to starting position and for simultaneously tensioning said spring, means motivated by said spring for actuating said chains at a uniform speed in a direction to effect the racing movement of the dummies, and means for effecting successive increases of speed of the respective chains during the racing movement, said last named means including chance controlled means for determining to which of said chains said speed increase is first applied.

3. In a racing game apparatus, the combination of a frame, parallel rectilinear track rails mounted on said frame, endless sprocket chains respectively mounted parallel with said track rails, dummies slidably mounted on said rails and attached to said chains, a power spring, manually operable means for actuating said chains in a direction to effect the return movement of the dummies to starting position and for simultaneously tensioning said spring, means motivated by said spring for actuating said chains at a uniform speed in a direction to effect the racing movement of the dummies, means for effecting successive increases of speed of the respective chains during the racing movement, said last-named means including chance controlled means for determining to which of said chains said speed increase is first applied, and means for varying the duration of said speed variations relatively to each other.

4. In an apparatus of the class described, means for propelling racing dummies back and forth at varying speeds over a rectilinear race track, comprising, in combination, shafts journaled crosswise of the starting and finish ends of said track, a plurality of sprockets loose on each of said shafts, the sprockets on one shaft being of larger diameter than those on the other shaft, endless chains trained over aligned sprockets, dummies attached to the respective chains, means for rotating said shafts, and chance controlled means for causing said chains to be successively driven by either said small or said large sprockets during the racing period.

5. In an apparatus of the class described, means for propelling racing dummies back and forth at varying speeds over a rectilinear race track, comprising, in combination, shafts journaled crosswise of the starting and finish ends of said track, a plurality of sprockets loose on each of said shafts, the sprockets on one shaft being of larger diameter than those on the other shaft, endless chains trained over aligned sprockets, dummies attached to the respective chains, means for rotating said shafts, clutch means for drivingly connecting said shafts to their respective sprockets, and chance controlled means acting through the clutch means on one of said shafts for causing said chains to be successively driven by either said small or said large sprockets during the racing period.

6. In an apparatus of the class described, means for propelling racing dummies back and forth at varying speeds over a rectilinear race track, com-

prising, in combination, shafts journaled crosswise of the starting and finish ends of said track, a plurality of sprockets loose on each of said shafts, the sprockets on one shaft being of larger 5 diameter than those on the other shaft, endless chains trained over aligned sprockets, dummies attached to the respective chains, means for rotating said shafts, said rotating means rotating both shafts simultaneously in the same direction, 10 clutches for drivingly connecting said shafts to their respective sprockets, and chance controlled means acting through the clutches of one group of sprockets for causing the latter to successively drive their respective chains at a speed 15 different from the driving speed of the other group.

7. In an apparatus of the class described, means for propelling racing dummies back and forth over a rectilinear race track comprising, in combination, shafts journaled crosswise of the starting and finish ends of said track, relatively small and large sprockets loose on said shafts at the starting and finish ends respectively, endless chains trained over aligned sprockets, dummies 20 attached to the respective chains, means for rotating said shafts in both directions, and chance controlled means for causing said chains to be successively driven by either said small or said large sprockets during the racing period.

8. In an apparatus of the class described, means for propelling racing dummies back and forth over a rectilinear race track comprising, in combination, shafts journaled crosswise of the starting and finish ends of said track, relatively small 35 and large sprockets loose on said shafts at the starting and finish ends respectively, endless chains trained over aligned sprockets, dummies attached to the respective chains, means for rotating said shafts in both directions, clutch means 40 for drivingly connecting said shafts to their respective sprockets, and chance controlled means acting through the clutch means on one of said shafts for causing said chains to be successively driven by either said small or said large sprockets 45 during the racing period.

9. In an apparatus of the class described, means for propelling racing dummies back and forth over a rectilinear race track comprising, in combination, shafts journaled crosswise of the starting and finish ends of said track, relatively small 50 and large sprockets loose on said shafts at the starting and finish ends respectively, endless chains trained over aligned sprockets, dummies attached to the respective chains, means for rotating said shafts in both directions, said rotating means rotating both shafts simultaneously in the same direction, clutches for drivingly connecting said shafts to their respective sprockets, and chance controlled means acting through the 55 clutches of said larger sprockets for causing the latter to successively drive their respective chains at increased speed.

10. In an apparatus of the class described, means for propelling racing dummies back and forth over a rectilinear race track comprising, in combination, shafts journaled crosswise of the starting and finish ends of said track, relatively small 60 and large sprockets loose on said shafts at the starting and finish ends respectively, endless chains trained over aligned sprockets, dummies attached to the respective chains, means for rotating said shafts in both directions, said driving 65 means rotating both shafts simultaneously in the same direction, clutches on the shaft at the starting end for driving its associated sprockets in one

direction, said clutches permitting over-running of their associated sprockets, normally open clutches on the shaft at the finish end, and chance controlled means for successively closing said last named clutches to thereby cause said large sprockets to pick up the chain drive from 5 said small sprockets and drive their respective chains at accelerated speed during the racing period.

11. In an apparatus of the class described, means for propelling racing dummies back and forth over a rectilinear race track comprising, in combination, shafts journaled crosswise of the starting and finish ends of said track, relatively small and large sprockets loose on said shafts at 10 the starting and finish ends respectively, endless chains trained over aligned sprockets, dummies attached to the respective chains, means for rotating said shafts in both directions, said driving means rotating both shafts simultaneously in 15 the same direction, clutches on the shaft at the starting end for driving its associated sprockets in one direction, said clutches permitting over-running of their associated sprockets, normally open clutches on the shaft at the finish end, chance 20 controlled means for successively closing said last-named clutches to thereby cause said large sprockets to pick up the chain drive from said small sprockets and drive their respective chains 25 at accelerated speed during the racing period, and friction clutches on the shaft at the starting end cooperating with the sprockets on said last-named shaft to drive said chains in the reverse direction when said shafts are rotated in the reverse direction, whereby to return the dummies to 30 starting position.

12. In an apparatus of the class described, means for propelling racing dummies back and forth over a rectilinear race track and lining them up at the starting end of said track comprising, in combination, shafts journaled crosswise of the starting and finish ends of said track, sprockets loose on said shafts, endless chains trained over aligned sprockets, dummies attached to the respective chains, means for rotating said shafts in both directions, clutches splined on one of said 40 shafts cooperating with the sprockets thereon to drive said chains in a direction to propel the dummies toward the finish end, chance controlled means for successively engaging said clutches with said sprockets, friction clutches on one of said shafts cooperating with the sprockets thereon to drive said chains in the reverse direction to return the dummies to the starting end of the track, and a bar extending 45 across said starting end against which the dummies are lined up, said friction clutches permitting slip of the sprockets engaged therewith when the dummies strike said bar.

13. In an apparatus of the class described, means for propelling racing dummies back and forth over a rectilinear race track and lining them up at the starting end of said track comprising, in combination, shafts journaled crosswise of the starting and finish ends of said track, sprockets loose on said shafts, endless chains trained over aligned sprockets, dummies attached to the respective chains, means for rotating the shaft at the starting end in both directions, pawl and ratchet clutches on said last-named shaft cooperating with the sprockets thereon to drive said chains in a direction to 60 propel the dummies toward the finish end, friction clutches on the same shaft cooperating with the sprockets thereon to drive said chains in the 65

reverse direction to return the dummies to the starting end, and a bar extending across said starting end against which the dummies are lined up, said friction clutches permitting slip of the sprockets engaged therewith when the dummies strike said bar.

14. In an apparatus of the class described, means for propelling racing dummies back and forth at varying speeds over a rectilinear race track, comprising, in combination, shafts journaled crosswise of the starting and finish ends of said track, a plurality of sprockets loose on each of said shafts, the sprockets on one shaft being of larger diameter than those on the other shaft, endless chains trained over aligned sprockets, dummies attached to the respective chains, means for rotating said shafts, clutches on said shafts through which rotation is imparted to said sprockets, clutch shifters associated with the clutches on one of said shafts, and means for actuating said clutch shifters to close said last-named clutches comprising a free-spin shaft, cams for engaging said clutch shifters spaced lengthwise of and around said free-spin shaft, and means for effecting step-by-step rotation of said free-spin shaft to bring said cams successively into engagement with said clutch shifters during the racing period.

15. In an apparatus of the class described, means for propelling racing dummies back and forth at varying speeds over a rectilinear race track, comprising, in combination, shafts journaled crosswise of the starting and finish ends of said track, a plurality of sprockets loose on each of said shafts, the sprockets on one shaft being of larger diameter than those on the other shaft, endless chains trained over aligned sprockets, dummies attached to the respective chains, means for rotating said shafts, clutches on said shafts through which rotation is imparted to said sprockets, clutch shifters associated with the clutches on one of said shafts, and means for actuating said clutch shifters to close and then open said last-named clutches comprising a free-spin shaft, pairs of cams for engaging said clutch shifters spaced lengthwise of and around said free-spin shaft to bring said pairs of cams successively into engagement with said clutch shifters during the racing period, one cam of each pair operating to close a clutch and the other to open the same clutch.

16. In a racing game apparatus wherein racing dummies are propelled over a race track by sprocket chains each trained over sprockets of unequal diameters and wherein both sprockets of each chain are convertible between driving and idler functions, means for successively converting the sprockets at one end of the chains from idler to driving sprockets to change the speed of the chains comprising normally open clutches associated with said last-named sprockets, clutch shifters, and means for actuating said clutch shifters comprising a free-spin shaft, cams for engaging said clutch shifters spaced lengthwise of and around said free-spin shaft, means for spinning said free-spin shaft during the return period of the dummies, and means for effecting step-by-step rotation of said free-spin shaft during the racing period.

17. In a racing game apparatus wherein racing dummies are propelled over a race track by sprocket chains each trained over sprockets of unequal diameters and wherein both sprockets of each chain are convertible between driving and idler functions, means for successively converting the

sprockets at one end of the chains from idler to driving sprockets to change the speed of the chains comprising normally open clutches associated with said last-named sprockets, clutch shifters, and means for actuating said clutch shifters comprising an endwise shiftable free-spin shaft and cams spaced lengthwise of and around the same, said free-spin shaft and its cams being in inoperative position relatively to said clutch shifters when the apparatus is idle, means for spinning said shaft and then shifting the same to operative position during the return period of the dummies, and means for effecting step-by-step rotation of said free-spin shaft during the racing period.

18. In a racing game apparatus wherein racing dummies are propelled over a race track by sprocket chains each trained over sprockets of unequal diameters and wherein both sprockets of each chain are convertible between driving and idler functions, means for successively converting the sprockets at one end of the chains from idler to driving sprockets to change the speed of the chains comprising normally open clutches associated with said last-named sprockets, clutch shifters, and means for actuating said clutch shifters comprising an endwise shiftable free-spin shaft and cams spaced lengthwise of and around the same, said free-spin shaft and its cams being in inoperative position relatively to said clutch shifters when the apparatus is idle, means for spinning said shaft and then shifting the same to operative position during the return period of the dummies, means for centering said shaft to bring one of its cams into operating engagement with a clutch shifter, and means for effecting step-by-step rotation of said free-spin shaft during the racing period to effect successive closing of the remaining clutches.

19. In a racing game apparatus wherein racing dummies are propelled over a race track by sprocket chains each trained over sprockets of unequal diameters and wherein both sprockets of each chain are convertible between driving and idler functions, means for successively converting the sprockets at one end of the chains from idler to driving sprockets to change the speed of the chains comprising normally open clutches associated with said last-named sprockets, clutch shifters, and means for actuating said clutch shifters comprising an endwise shiftable free-spin shaft and cams spaced lengthwise of and around the same, said free-spin shaft and its cams being in inoperative position relatively to said clutch shifters when the apparatus is idle, means for spinning said shaft and then shifting the same to operative position during the return period of the dummies, means for centering said shaft to bring one of its cams into operating engagement with a clutch shifter, means for effecting step-by-step rotation of said free-spin shaft during the racing period to effect successive closing of the remaining clutches, and means for varying the time periods between successive rotary movements of said free-spin shaft.

20. In a racing game apparatus wherein racing dummies are propelled back and forth over a race track by propulsion devices individual to the respective dummies, and wherein means are provided for successively varying the speed of the several propulsion devices, means for effecting chance actuation of said speed-varying means comprising a free-spin shaft, cams on said shaft for successively putting in operation said speed-varying means, a ratchet on said shaft, a slide

mounted adjacent to said shaft, and a dog on said slide adapted to hit said ratchet and spin said shaft.

21. In a racing game apparatus wherein racing dummies are propelled back and forth over a race track by propulsion devices individual to the respective dummies, and wherein means are provided for successively varying the speed of the several propulsion devices, means for effecting chance actuation of said speed-varying means comprising a free-spin shaft, cams on said shaft for successively putting in operation said speed-varying means, a ratchet on said shaft, a slide mounted adjacent to said shaft, a dog on said slide adapted to hit said ratchet and spin said shaft, and means for actuating said slide and effecting the spinning of said shaft during the return travel of the dummies to starting position.

22. In a racing game apparatus wherein racing dummies are propelled back and forth over a race track by propulsion devices individual to the respective dummies, and wherein means are provided for successively varying the speed of the several propulsion devices, means for effecting chance actuation of said speed-varying means comprising a free-spin shaft, cams spaced around said shaft for successively putting in operation said speed-varying means, a ratchet on said shaft, a slide mounted adjacent to said shaft, a dog on said slide adapted to hit said ratchet and spin said shaft, means for actuating said slide and effecting the spinning of said shaft during the return travel of the dummies to starting position, and means for rotating said shaft step-by-step during the racing period.

23. In a racing game apparatus wherein racing dummies are propelled back and forth over a race track by propulsion devices individual to the respective dummies, and wherein means are provided for successively varying the speed of the several propulsion devices, the combination of a motor spring and means driven thereby for actuating said propulsion devices during the racing period, a handle lever and means driven thereby for actuating said propulsion devices during the return period and simultaneously therewith tensioning said spring, means for effecting chance actuation of said speed-varying means comprising a free-spin shaft, cams on said shaft for successively putting in operation said speed-varying means, a ratchet on said shaft, a slide mounted adjacent to said shaft, a dog on said slide adapted to hit said ratchet and spin said shaft, and means actuated by said handle lever for operating said slide.

24. In a racing game apparatus wherein racing dummies are propelled back and forth over a race track by propulsion devices individual to the respective dummies, and wherein means are provided for successively varying the speed of the several propulsion devices, the combination of a motor spring and means driven thereby for actuating said propulsion devices during the racing period, a handle lever and means driven thereby for actuating said propulsion devices during the return period and simultaneously therewith tensioning said spring, means for effecting chance actuation of said speed-varying means, comprising a free-spin shaft, cams spaced lengthwise of and around said shaft, said shaft and its cams being normally in a position inoperative to actuate said speed-varying means, means actuated by said handle lever for spinning said shaft when in inoperative position, and

means controlled by said handle lever for then centering said shaft to operatively relate the cams thereon angularly to said speed-varying means.

25. In a racing game apparatus wherein racing dummies are propelled back and forth over a race track by propulsion devices individual to the respective dummies, and wherein means are provided for successively varying the speed of the several propulsion devices, the combination of a motor spring and means driven thereby for actuating said propulsion devices during the racing period, a handle lever and means driven thereby for actuating said propulsion devices during the return period and simultaneously therewith tensioning said spring, means for effecting chance actuation of said speed-varying means comprising a free-spin shaft, cams spaced lengthwise of and around said shaft, said shaft and its cams being normally in a position inoperative to actuate said speed-varying means, means actuated by said handle lever for spinning said shaft when in inoperative position, means controlled by said handle lever for then centering said shaft to operatively relate the cams thereon angularly to said speed-varying means, and means actuated by said handle lever for then shifting said shaft to operative position.

26. In a racing game apparatus wherein racing dummies are propelled back and forth over a race track by propulsion devices individual to the respective dummies, and wherein means are provided for successively varying the speed of the several propulsion devices, the combination of a motor spring and means driven thereby for actuating said propulsion devices during the racing period, a handle lever and means driven thereby for actuating said propulsion devices during the return period and simultaneously therewith tensioning said spring, means for effecting chance actuation of said speed-varying means, comprising a free-spin shaft, cams spaced lengthwise of and around said shaft, said shaft and its cams being normally in a position inoperative to actuate said speed-varying means, means actuated by said handle lever for spinning said shaft when in inoperative position, means controlled by said handle lever for then centering said shaft to operatively relate the cams thereon angularly to said speed-varying means, means actuated by said handle lever for then shifting said shaft to operative position, and mechanism operated by said motor spring for then imparting a step-by-step rotation to said shaft whereby to successively actuate said speed-varying means.

27. In a racing game apparatus wherein racing dummies are propelled back and forth over a race track by propulsion devices individual to the respective dummies, and wherein means are provided for successively varying the speed of the several propulsion devices, the combination of a motor spring and means driven thereby for actuating said propulsion devices during the racing period, a handle lever and means driven thereby for actuating said propulsion devices during the return period and simultaneously therewith tensioning said spring, means for effecting chance actuation of said speed-varying means, comprising a free-spin shaft, cams spaced lengthwise of and around said shaft, said shaft and its cams being normally in a position inoperative to actuate said speed-varying means, means actuated by said handle lever for spinning said shaft when in inoperative position,

in inoperative position, spring-actuated means controlled by said handle lever for then centering said shaft to operatively relate the cams thereon angularly to said speed-varying means, means actuated by said handle lever for then shifting said shaft to operative position, and mechanism operated by said motor spring for then imparting a step-by-step rotation to said shaft, said mechanism including parts brought into cooperative engagement by the shifting of said shaft.

28. In a racing game apparatus wherein racing dummies are propelled back and forth over a race track by propulsion devices individual to the respective dummies, and wherein means are provided for successively varying the speed of the several propulsion devices, means for effecting chance actuation of said speed-varying means, comprising a free-spin shaft, cams spaced around said shaft for successively actuating said speed-varying means, a pinion fast on said shaft, a rack engaged with said pinion, and means for effecting a step-by-step movement of said rack during the racing period.

29. In a racing game apparatus wherein racing dummies are propelled back and forth over a race track by propulsion devices individual to the respective dummies, and wherein means are provided for successively varying the speed of the several propulsion devices, means for effecting chance actuation of said speed-varying means, comprising a free-spin shaft, cams spaced around said shaft for successively actuating said speed-varying means, a pinion fast on said shaft, a rack engaged with said pinion, means for effecting a step-by-step movement of said rack during the racing period, and means for varying the time intervals between successive movements of said rack.

30. In a racing game apparatus wherein racing dummies are propelled back and forth over a race track by propulsion devices individual to the respective dummies, and wherein means are provided for successively varying the speed of the several propulsion devices, means for effecting chance actuation of said speed-varying means, comprising a free-spin shaft, cams spaced around said shaft for successively actuating said speed-varying means, a pinion fast on said shaft, a rack engaged with said pinion, an escapement lever cooperating with said rack for effecting a step-by-step movement of the latter during the racing period, a spring actuating said escapement lever in one direction, a lever actuating said escapement lever in the reverse direction, and a rotary disc carrying a plurality of cams successively rocking said escapement-actuating lever.

31. In a racing game apparatus wherein racing dummies are propelled back and forth over a race track by propulsion devices individual to the respective dummies, and wherein means are provided for successively varying the speed of the several propulsion devices, means for effecting chance actuation of said speed-varying means, comprising a free-spin shaft, cams spaced around said shaft for successively actuating said speed-varying means, a pinion fast on said shaft, a rack engaged with said pinion, an escapement lever cooperating with said rack for effecting a step-by-step movement of the latter during the racing period, a spring actuating said escapement lever in one direction, a lever actuating said escapement lever in the reverse direction, and a rotary disc carrying a plurality of cams spaced at unequal distances apart on and around its periph-

ery for successively rocking said escapement-actuating lever.

32. In a racing game apparatus wherein racing dummies are propelled back and forth over a race track by propulsion devices individual to the respective dummies, and wherein means are provided for successively varying the speed of the several propulsion devices, means for effecting chance actuation of said speed-varying means, comprising a free-spin shaft, cams spaced around said shaft for successively actuating said speed-varying means, a pinion fast on said shaft, a rack engaged with said pinion, an escapement lever cooperating with said rack for effecting a step-by-step movement of the latter during the racing period, a spring actuating said escapement lever in one direction, a lever actuating said escapement lever in the reverse direction, and a rotary disc carrying a plurality of cams spaced at unequal distances apart on and around its periphery and having arcuate peaks of unequal lengths for successively rocking said escapement-actuating lever.

33. In a racing game apparatus, wherein racing dummies are propelled back and forth over a race track by sprocket chains on which the dummies are mounted, the combination of a frame, shafts journaled in and crosswise of the respective ends of the frame, sprockets on said shafts over which the chains are trained, clutches on said shafts for placing the sprockets in driven or idle relation to their respective shafts, a power shaft journaled in and crosswise of said frame, a transmission shaft journaled in and crosswise of said frame, a power spring, means actuated by said power shaft for turning said transmission shaft in one direction and simultaneously tensioning said power spring, sprockets fast on said first-named shafts, a chain trained over said last-named sprockets, a sprocket on said transmission shaft drivingly engaged with said last-named chain, a handle lever, and means through which a movement of said handle lever in one direction imparts a turning movement to said power shaft in a direction to tension said power spring.

34. In a racing game apparatus, wherein racing dummies are propelled back and forth over a race track by sprocket chains on which the dummies are mounted, the combination of a frame, shafts journaled in and crosswise of the respective ends of the frame, sprockets on said shafts over which the chains are trained, clutches on said shafts for placing the sprockets in driven or idle relation to their respective shafts, a power shaft journaled in and crosswise of said frame, a transmission shaft journaled in and crosswise of said frame, a power spring anchored at one end thereof, a sprocket fast on said transmission shaft, a quadrant fast on said power shaft, a chain attached at one end to said quadrant, passing over said last-named sprocket, and at its other end connected to the other end of said power spring, sprockets fast on said first-named shafts, a chain trained over said last-named sprockets, a second sprocket on said transmission shaft drivingly engaged with said last-named chain, a handle lever, and means through which a movement of said handle lever in one direction imparts a turning movement to said power shaft in a direction to tension said power spring.

35. In a racing game apparatus, wherein racing dummies are propelled back and forth over a race track by sprocket chains on which the dummies are mounted, the combination of a

frame, shafts journaled in and crosswise of the respective ends of the frame, sprockets on said shafts over which the chains are trained, clutches on said shafts for placing the sprockets in driven or idle relation to their respective shafts, a power shaft journaled in and crosswise of said frame, a transmission shaft journaled in and crosswise of said frame, a power spring, means actuated by said power shaft for turning said transmission shaft in one direction and simultaneously tensioning said power spring, sprockets fast on said first-named shafts, a chain trained over said last-named sprockets, a sprocket loose on said transmission shaft drivingly engaged with said last-named chain, clutches on said transmission shaft for respectively driving said loose sprocket in opposite directions, a handle lever, and means through which a movement of said handle lever in one direction imparts a turning movement to 20 said power shaft in a direction to tension said power spring; said last-named means including automatic mechanism by which the power load is transferred to said power spring to cause the latter to operate the apparatus during the racing period.

36. In a racing game apparatus, wherein racing dummies are propelled back and forth over a race track by sprocket chains on which the dummies are mounted, the combination of a frame, shafts journaled in and crosswise of the respective ends of the frame, sprockets on said

shafts over which the chains are trained, clutches on said shafts for placing the sprockets in driven or idle relation to their respective shafts, a power shaft journaled in and crosswise of said frame, a transmission shaft journaled in and crosswise of said frame, a power spring anchored at one end thereof, a sprocket fast on said transmission shaft, a quadrant fast on said power shaft, a chain attached at one end to said quadrant, passing over said last-named sprocket, and at its 10 other end connected to the other end of said power spring, sprockets fast on said first-named shafts, a chain trained over said last-named sprockets, a second sprocket loose on said transmission shaft drivingly engaged with said last-named chain, clutches on said transmission shaft for respectively driving said second sprocket in opposite directions, a handle lever, and means through which a movement of said handle lever in one direction imparts a turning movement to 20 said power shaft in a direction to tension said power spring; said last-named means including contacting members through which the movement is transmitted and means automatically causing one of said members to slide out of contact with the other near the end of the movement of said handle lever, whereby the power load is transferred to said power spring to cause the latter to operate the apparatus in the reverse direction during the racing period.

JOHN WATLING.
